CLOCK OR SIMILAR ARTICLE

Mark Wallach, 220 E. 63rd St.,
New York, N.Y. 10021

Filed Oct. 1, 1971, Ser. No. 185,922

Term of patent 14 years

Int. Cl. D10—01

U.S. Cl. D10—21

FIG. 1 is a front perspective view of a clock or similar article showing my new design;

FIG. 2 is a rear perspective view thereof;

FIG. 3 is a front perspective view of another embodiment of the new FIG. 1 design wherein the dial face has been changed from hexagonal to diamond; and

FIG. 4 is a rear perspective view thereof.

I claim:

The ornamental design for a clock or similar article, as shown and described.
